MANUAL VALVE

William A. Ray, North Hollywood, and Laurence C. Biggle, Altadena, Calif., assignors to General Controls Co., Glendale, Calif., a corporation of California

Application July 11, 1955, Serial No. 36,910

Term of patent 14 years

(Cl. D78—1)

Figure 1 of the drawing is a plan view of a manual valve embodying our new design;

Figure 2 is a side elevation thereof; and

Figures 3 and 4 are end views thereof taken from the right and from the left, respectively.

The side of the valve not shown is the same as the side shown when viewed in a mirror.

We claim:

The ornamental design for a manual valve, substantially as shown and described.
